UNITED STATES PATENT OFFICE.

JOHN GEORGE LEYNER, OF DENVER, COLORADO.

ROCK-DRILLING ENGINE.

SPECIFICATION forming part of Letters Patent No. 783,638, dated February 28, 1905.

Application filed September 2, 1903. Serial No. 171,624.

To all whom it may concern:

Be it known that I, JOHN GEORGE LEYNER, a citizen of the United States of America, residing in the city and county of Denver and State of Colorado, have invented certain new and useful Improvements in Rock-Drilling Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in rock-drilling engines; and the objects of my invention are, first, to provide means for automatically starting the flow of water when the drilling-engine is started and for stopping the flow of water when the drilling-engine is stopped; second, to provide a combined air and spring controlled valve for controlling the supply and flow of water through the rock-drilling engine to its rock-cutting drill-bit; third, to provide means for adjusting the pressure of the water-controlling valve against its seat; fourth, to provide a small compact light-weight rock-drilling engine of great rock-drilling power. I attain these objects by the mechanism illustrated in the accompanying drawings, in which—

Figure 1 is a plan view of a rock-drilling engine embodying my invention. Fig. 2 is a side elevation of Fig. 1. Fig. 3 is a longitudinal central section of Figs. 1 and 2. Fig. 4 is a rear end elevation of Figs. 1 and 2. Fig. 5 is a section of Figs. 1 and 3 on line 5-5. Fig. 6 is a section of Figs. 1 and 3 on line 6-6. Fig. 7 is a fragmentary section of Fig. 3 on line 7-7. Fig. 8 is a section through Fig. 3 on line 8-8. Fig. 9 is a section of Fig. 3 on line 9-9. Fig. 10 is a section of Fig. 2 on line 10-10. Fig. 11 is an end elevation of the rear cylinder-head. Fig. 12 is a section of Fig. 11. Fig. 13 is a side elevation of the drill-holding chuck. Fig. 14 is a side elevation of the drill-bit's pawl-holding piston. Fig. 15 is a central longitudinal section of Fig. 14. Fig. 16 is a section through the pawl-piston's cylinder. This view is also a cross-section on line 8-8 of Fig.

3 through the front cylinder-head, as this transversely-arranged pawl-piston cylinder forms a part of the front cylinder-head. Fig. 17 illustrates a perspective view of the drill-chuck, a fragment of the hammer-striking end of the 55 drill-bit, and a perspective view of the chuck-ring by which the drill-bit is locked to the chuck. Fig. 18 is a side elevation of the rock-cutting drill-bit which I preferably use in my rock-drilling engine, and Fig. 19 is a perspective view of the chuck-ring wrench which is used to turn the chuck-ring and unlock the drill-bit, from the chuck whenever the drill-bit gets stuck in seams in rock while drilling them. Fig. 20 is an enlarged sectional view through 65 the water-tube-supporting disk, showing a tapered plug seated in a tapered bore therein, which is adapted to clamp and hold one end of the water-tube, the rear cylinder-head and a portion of the cylinder being shown in dotted lines. Fig. 21 is a transverse sectional view on the line 21-21 of Fig. 20, showing a screen which is secured within an annular recess in the hub of the disk, the said screen being designed to cover a plurality of holes which 70 form a communication between the annular recess and the bore of the disk. Fig. 22 is a side elevation of the disk, clearly showing the annular recess in its hub portion and the screen secured therein. Fig. 23 is a perspective view of the tapered plug which is seated in the tapered bore of the disk; and Fig. 24 is a transverse sectional view thereof, more fully showing the slots which extend from its longitudinal bore through its periphery. 80

Similar figures of reference refer to similar parts throughout the several views.

Referring to the drawings, the numeral 1 designates the cylinder of my improved rock-drilling engine.

The numeral 2 designates the valve-chest, which is formed integral with the cylinder. Suitable air inlet and exhaust ports 5 and 6 are formed in the cylinder, which extend from the central portion of the cylinder to its opposite ends, and a center port 7, that is positioned between the ports 5 and 6. The ports 5 and 6 connect by lateral ports 5^A and 6^A with the ports 8 and 9, both of which lead to the front end of the drilling-engine, as will 95 100

be explained hereinafter. The valve-chest is provided with air-inlet ports 10, 11, and 12 and with exhaust-ports 13 and 14. The ports 10 and 12 register with the ports 5 and 6. The 5 port 11 forms the air-entrance port into the valve-chest and registers with an inlet formed in projecting hub 11^A, the entrance to which is interiorly threaded. The exhaust-ports 13 and 14 register with outlets formed in projecting hubs 13^A and 14^A. A valve 15 is operatively mounted in the valve-chest and is provided with collars 16, which are arranged on a stem 17 to control the ports 10, 11, 12, 13, and 14. An operative piston 19 is reciprocally mounted in the cylinder and is provided with a circumferential recess 20 at the central portion of its length, which connects with ports 20^A, 20^B, 20^C, and 20^D, which operate with the ports in the valve-chest to operate the valve and piston. An air-port 18 extends from the air-inlet port 11 (see Fig. 10) rearward to the end of the cylinder, where it intersects a recess in the rear cylinder-head, which I will fully describe hereinafter. 15

25 The cylinder 1 is provided with a rear cylinder-head 21. This rear cylinder-head is a cylindrical hood-shaped member. A circular flange comprises the inner end of this cylinder-head, and this flange abuts against the end 30 of the cylinder. The peripheral edge and back of the flanged end of the rear cylinder-head is provided with a right-angled stepped shoulder 22. I preferably secure the rear cylinder-head to the cylinder by means of a 35 ring 23, the inner periphery of which is provided with a thread that screws onto a thread formed on the adjacent end of the cylinder. The outer end of this ring 23 is provided with an open-ended flange portion 24, that extends 40 over the body of the rear cylinder-head and fits in and against the stepped shoulder 22 of the rear cylinder-head. By removing the ring the cylinder-head may be turned to permit its water-coupling inlet to be turned to 45 stand on either one side or the other of the drilling-engine.

24^A designates the front cylinder-head. This cylinder-head is also a hood-shaped cylindrical member which is preferably threaded 50 to the cylinder by a reduced shouldered threaded end that screws into a threaded counterbore formed in the end of the cylinder. I will describe the front cylinder-head more fully hereinafter.

55 The bottom of the cylinder adjacent to its rear end is provided with a depending lug 25, through which a nut 26 is extended. This nut is provided with a shoulder 27 at one end, which bears against one end of the depending lug, 60 while its opposite end extends through the lug and is threaded, and a nut 28 is threaded to it and screws against the opposite end of the depending lug, thus rigidly securing the nut to the lug. The interior of this nut is threaded, 65 and a long feed-screw 29 is threaded loosely

to it. One end of this screw extends rearwardly of the cylinder, and its extreme end is provided with a thread, and adjacent to this threaded end a collar 30 is formed. The threaded end of the feed-screw extends loosely 70 through a hole 30^A, formed in the center of a cross-bar 31, and the collar 30 extends into a counterbored hole 30^B, formed in the cross-bar concentric to the hole 30^A to receive it, and the hub end of a crank 32 is threaded to the 75 end of the feed-screw and screws against the cross-bar, the hub of the crank and the collar being arranged to loosely clamp the feed-screw to the cross-bar. The hub of the crank is split through into its threaded hole that screws onto the feed-screw by a slot 32^A, and a bolt 33 extends through the ends of the hub formed by the slot and clamps the threaded hub of the crank to the end of the feed-screw, thus additionally securing the crank to the feed-screw. 80 The cylinder is also provided with a depending portion, on the opposite sides of which are formed slideways 34 and 35. These slideways form an integral part of the depending lug 25. These slideways are fitted slidably in the 85 guideways 36 and 37 of a supporting-shell 38. This supporting-shell is preferably longer than the cylinder and forms the supporting-base for it. Adjacent to its forward end an outwardly-diverging hub 39 is formed on its 90 bottom, which is adapted to be clamped to the chuck of a stoping-bar or a tripod, which I do not illustrate. To the opposite sides of the 95 rear end of the shell I secure one of the ends of two rods 40 and 41. These rods extend rearwardly from the shell, and their opposite ends are secured to the opposite ends of the cross-bar 31, to the center of which the crank end of the feed-screw is rotatably secured. The cylinder is adapted to be fed reciprocally through 100 the shell by the feed-screw. The cylinder is provided with a piston-bore 42, in which I reciprocally fit a hammer-piston 19. This hammer-piston comprises a piston-head 44 and a hammer-bar extension 45, which is formed integral with the piston-head. This hammer-bar extension projects forward from the front end of the piston into a sleeve 46, which is rotatably mounted in the axial bore of the front cylinder-head, as will be fully explained hereinafter. 105 In the front end of the cylinder I form a counterbore 47 of larger diameter than the piston's bore, in which I fit a steel buffer-ring 48, which I term the "cylinder-ring," and against this ring I place a rubber buffer-ring 49, and at the side of the rubber ring I place a supplementary steel buffer-ring 50, which is positioned in a counterbore 51, which I preferably form larger in diameter than the counterbore in which the rings 48 and 49 are placed. 110 The front cylinder-head screws into the cylinder and against the shoulder 55, that is formed on the front cylinder-head, and up against the ring 50, which acts as an abutment for the buffer-rings 48 and 49. Those rings surround 115

120

125

130

135

the hammer-bar. In the opposite end of the cylinder adjacent to the rear cylinder-head a steel buffer-ring 53 is placed in a counterbore 54, against which the piston strikes on its 5 backward stroke. A rubber buffer-ring 55 is placed at the side of the steel buffer-ring, and between it and the rear cylinder-head I place a water-pipe-supporting disk 56, which sets in a counterbore formed partially in the end 10 of the cylinder and partially in a counterbore that forms a part of an axial aperture 56^A, which I term the "water-pipe-valve chamber" that extends a short distance into the rear cylinder-head from its inner end. The rear end 15 of the rear cylinder-head contains an axial aperture 57, that extends into it for a short distance, which is interiorly threaded for a portion of its length from its end. In this threaded end I screw a hollow thimble-nut 58, 20 the outer end of which is solid and is provided with a hexagon nut portion, by which the thimble may be screwed into and out of the rear cylinder-head, and on the thimble I place a check-nut 59, which is adapted to screw 25 against the end of the rear cylinder-head and lock the thimble in an adjusted position. In the axial aperture 57, adjacent to the thimble, I slidably fit a circular valve-stem-operating piston 59^A, which is adapted to be moved in 30 its bore by air-pressure from the valve of the drilling-engine, as will be explained hereinafter. The periphery of this piston is provided with circumferential recesses 60, which are formed simply to collect any dirt that may 35 accumulate in its seat. This valve-stem-operating piston, the thimble, and the adjacent partition 61 of the rear cylinder-head between the axial aperture 57 and the valve-chamber are provided with an axial-bore 62, in which is 40 slidably fitted a valve-stem 63. This valve-stem projects through and beyond the thimble, and a handle-ring 64 is loosely secured in a hole 65 in its end. This valve-stem is provided with a collar portion 65^A, the inside of 45 which tapers and converges to the body of the valve-stem, thus forming a circular tapering valve-disk 67 on the valve-stem. This valve-disk is arranged to operatively rest against a tapering seat 68, formed in the bottom 50 of a counterbore 69, which is formed in the outer end of the valve-stem's operating piston concentric to its axial bore. Around the valve-stem in the thimble I place a coiled spring 69^A, which is arranged to bear expansively 55 against the inner end of the thimble and the valve-disk 65^A and hold the valve at the opposite end of the valve-stem against its seat, as will be described fully hereinafter, and at the same time holding the valve-actuating piston against or close to the partition 61. When the drilling-engine is not in operation, the tension of the spring is adjusted by screwing the thimble in or out of the rear cylinder-head to obtain the desired pressure of the 60 valve-disk against its seat, after which the

thimble may be locked in its adjusted position by the check-nut 59. The opposite end of the valve-stem extends through and beyond the piston guide-block and through a cupped leather washer 70, that is fitted tightly round 70 the valve-stem and is seated in an axial aperture 71, formed in the bottom of the valve-chamber 56^A. This cupped washer is held in place by a hub portion 72, formed on the water-pipe-supporting disk, which projects into 75 the counterbore in the partition against the cupped washer. This hub portion of the water-pipe disk is provided with an axial aperture 73, which extends into it for a short distance as a straight hole and then continues 80 through the axial center of the disk as a taper hole, and transversely through the straight portion of the hub holes 74 are formed, which register with the valve-chamber 56^A in the rear cylinder-head. I fit a taper plug 75 in 85 the taper portion of the hole in the pipe-disk and make the plug long enough to extend from the inner edges of the transverse holes through the shell of the hub from its outer end through the disk and far enough beyond it to thread 90 a nut 76 on its end. This plug is provided with an axial hole of two diameters and with radial slots 75^A, extending from its axial hole through its shell portion intermediate of its ends, thus dividing it for a portion of its 95 length adjacent to the end of its threaded end with axially-aligned portions of its shell that are compressed toward the axis of said plug to clamp the end of the water-tube by being drawn into the taper hole in the disk by the 100 nut. The smallest axial hole in the plug extends into it from the valve-stem end. The entrance to this hole is counterbored to form an outwardly-flanged or tapering valve-seat, and on the end of the valve-stem a tapering 105 plug-valve 77 is formed, that is arranged and adapted to bear and be held tight against this seat by the expansive spring 69^A. The larger hole in the plug 75 extends into it to near its opposite end concentric to the smaller hole, and in this hole I fit snugly one end of a water-conveying tube 78 and secure it rigidly to the plug by screwing the nut to draw the plug in its taper hole and force its finger portions to 110 clamp the pipe. This water-conveying pipe extends through a hole formed axially through the piston-hammer and its extension hammer-bar and into the end of a hollow rock-cutting drill-bit 79, that extends into the front cylinder-head and the drill-chuck sleeve 46. I 115 preferably form the aperture in the hammer through which the water-pipe extends of three diameters. Thus at the pipe's entrance end into the hammer I form a hole 80, much larger in diameter than the pipe, and fit a brass bushing into it, in which the pipe fits slidably. The hole extending from the bushing is also considerably larger than the pipe. This sized hole extends to near the end of the hammer-bar, where a hole but a little larger in diameter than the 120

pipe is formed. In Fig. 3 the opposite ends of the water-pipe are illustrated in section in order to clearly illustrate that it is a pipe. The valve-stem-actuating piston automatically 5 controls the admittance of water to the water-pipe when the drilling-engine is running by means of a supply of air that flows to it from the port 11 of the valve-chest through the ports 18 in the shell or casing of the cylinder, 10 where it intersects a circumferential recess 18^A, that is formed in the face of the flange of the rear cylinder-head. From the top of this recess a horizontal port-hole 18^B is drilled into the head, which is intersected by a vertical 15 port-hole drilled downward from the top of the flange of the rear head. This hole 18^B intersects a horizontal port-hole 18^C, drilled into the rear cylinder-head from its cylinder to opposite the inner end of the valve-stem's 20 operating-piston, where it intersects a vertical port-hole 18^D, drilled through the shell of the rear cylinder-head close to the partition at the rear of the piston. As I preferably 25 drill the several holes that form this air-port, it is necessary to plug their entrance ends with plugs after they are drilled. The front end of the valve's actuating-piston is provided 30 concentric to the valve-stem with a slightly-projecting hub portion that strikes the partition, which leaves an annular space between 35 the back of the piston and the partition, that registers with the entrance to the air-port and permits the air to flow directly around the end of the piston.

35 On one side of the rear cylinder-head a projecting hub 82 is formed, in which a water-inlet aperture 83 is formed. (See Figs. 11 and 12.) The end of this water-inlet hub is threaded to receive a hose-coupling. The water- 40 inlet aperture in this hub extends only a short distance into the rear cylinder-head, and from its bottom a passage 84 extends into the valve-chamber 56^A of the water-pipe.

In order to prevent sand, grit, or any sediment in the water from reaching the valve-seat, I place a fine-mesh screen 85 around the hub of the water-pipe-supporting disk, preferably securing it in place by soldering it to the hub, and in order that the water may have 45 a large space all round the screen and clear access to all the apertures in the shell of the hub after it has passed the screen I form a circumferential recess 85^A around the hub, and the apertures are placed in the bottom of 50 this recess. The rear cylinder-head can be turned on its seat against the cylinder to allow the water-inlet-hose-coupling hub to be placed on either side or on the top or bottom of the axial center of the drilling-engine in 55 order to allow the water-supply hose to be connected to it at either one of the four sides of the drill in the most convenient position by loosening the ring 28, which is provided with shallow holes 28^A in its periphery, in 60 which a suitable spanner-wrench may be 65

placed, with which the ring may be screwed on or off. The air-port recess 18^A being arranged entirely around the flange of the rear cylinder-head to permit the head to be turned for this purpose and in order to permit the 70 water-inlet coupling to be turned accurately to the opposite horizontal and vertical quarter-points of the axial center of the drilling-engine, I secure a dowel-pin 86 in the end cylinder and form four holes 87 at the vertical and horizontal quarters of the rear cylinder-head, (see Fig. 11,) which fit loosely over the end of the dowel-pin that projects from the end of the cylinder.

The front cylinder-head comprises a long 80 cylindrical member that is adapted to support the rock-cutting drill-bit and its step-by-step rotative mechanism. A transverse cylindrical portion 86^B is formed on the cylinder-head intermediate of its ends, the axial bore of which 85 extends at right angles to the axial bore of the cylinder-head. This right-angled-disposed cylinder extends, preferably, an equal distance on each side of the axial center of the front cylinder-head. The opposite ends of this cylinder are slightly counterbored and are 90 interiorly threaded, and cylinder-heads 87^A and 88 are threaded into the ends of the cylinder. In the bore of this cylinder a pawl-carrying 95 piston 89 is slidably fitted. This piston is a little shorter than the cylinder and has but a short stroke therein and is operatively reciprocated by the actuating fluid used to operate the rock-drilling engine, which is preferably compressed air, which flows to the opposite 100 ends of the pawl-piston cylinder from the ports 5 and 6 of the piston-hammer's cylinder through the ports 8 and 9, which extend from these ports through the shell of the cylinder and front cylinder-head to the pawl-piston's 105 cylinder. The ports 8 and 9 are arranged on opposite sides of the main cylinder and extend to the opposite ends of the pawl-piston cylinder, and as these ports are rather crooked 110 I will describe the course of port 8. As the pawl-piston is a small light piece of steel, the power required to reciprocate it in its cylinder is but a trifle. The ports are small 115 passages, which I preferably make by drilling holes in the shell to form the ports, and as both ports are exactly alike, except that the port 9 is a little longer than the port 8, a description of one will apply to the other. The end 90 of the port 8 is drilled into the shell 120 of the cylinder from the shoulder 91 at the bottom of the counterbore 47 in the front end of the cylinder. The end portion 90 of the port 8 is intersected by a short inclined vertical hole 93, which is drilled from the top of the cylinder downward toward the axial center of the main cylinder into the port 8. This 125 vertical portion of the port 8 is intersected by a horizontal hole 94, which is drilled into the front end of the cylinder. The portion 94 of the port 8 is intersected near the end of 130

the cylinder by a vertically-inclined hole 95, which extends downward from the top of the cylinder and through the same into the front cylinder-head, where its lower end is intersected by a horizontal hole 96, which is drilled into the adjacent end of the front cylinder-head. The hole 96 is intersected by a horizontal hole 97, that is drilled into the side, of the front cylinder-head at substantially right angles to the hole 96. The portion 97 is intersected by an inclined hole 98, that is drilled from the top of the front cylinder-head into the pawl-piston cylinder. As the front head screws into the cylinder provision must be made to bring both parts of the hole 95 to connect. I accomplish this by forming short circumferential recesses 92 in the periphery of the threaded end of the cylinder-head, which provides an offsetting passage that permits a clear passage even if the cylinder-head is screwed not quite to or beyond the position it occupies when the hole is drilled. The only difference between the port 8 and the port 9 is that the port 9 extends along the opposite side of the cylinder and that the portion 99 of the portion 9 which corresponds to the portion 90 of the port 8 extends to the port 5. The air enters and exhausts from the pawl-piston cylinder through the ports 8 and 9 and reciprocates the pawl-piston therein. The center of the pawl-piston is provided with an oblong aperture 101, which extends transversely through its axial length and which is positioned to surround the axial center of the main cylinder. This oblong aperture 101 is longest along the length of the pawl-piston, and in the central portion of its inner periphery recesses 102 and 103 are formed—one at the top portion and one at the lower portion of the aperture—in which are pivotally secured and positioned pawls 104 and 105. Suitable springs 106 and 107 are arranged in the piston to bear resiliently on the tooth end of the pawls. Either coiled springs or wire springs or blade-springs may be used for this purpose, and they may be arranged in any suitable manner; but I preferably use the spring-wire springs illustrated. One end of each of these springs may be secured to the piston by any suitable means, while their opposite ends are arranged in the recesses 102 and 103 to bear resiliently against the pawls. I illustrate but two pawls; but more can be used, if desired. I arrange these pawls and the receiving-recesses in diametrically opposite corners of the aperture in the piston. The tooth ends of the pawls 104 and 105 bear operatively on a circumferential row of ratchet-teeth 108, that are formed in the peripheral surface of the drill-holding chuck 46. This drill-holding chuck comprises a tubular sleeve member, which is rotatably mounted in the axial bore of the front cylinder-head. The bore of the front cylinder-head is made in two diameters, the inner diameter being the largest.

The chuck is also made in two diameters and is inserted in the cylinder-head from its main cylinder end, its larger portion fitting in the larger diameter of the bore in the cylinder-head and fitting rotatably between the shoulder at the bottom of the counterbore and the steel buffer-ring. The drill-holding chuck is provided with an axial bore of two diameters 110 and 111, the bore 111 of which is the largest and is made to surround loosely the piston-hammer, which reciprocates in it. The smaller bore 110 of the drill-chuck is adapted to receive loosely the shank end of the drill-bit. The outer end of the drill-chuck extends slightly beyond the end of the front cylinder-head and is arranged to receive the shank end of the rock-cutting drill-bits in such a manner that they are locked to it and are rotated by it, but at the same time are free to be almost instantaneously inserted into and withdrawn from it. The outer end of the front cylinder-head is threaded, and a shoulder 112 is formed at the end of the thread. A cap 113 is threaded to the threaded end of the cylinder. The drill-bit-receiving end of the chuck is bifurcated diametrically to form the slots 114 and 115, (see Fig. 17,) and the opposite ends 116 and 118 are provided with step-portions 119 and 120, of less diameter, that extend circumferentially around each end about one-half of its semicircular periphery. The drill-bit 79 consists of a shank portion 122 and any suitable rock-cutting end portion 123. The shank is provided adjacent to its end with projecting lugs 123^A, two, preferably, being used, which are formed on diametrically-opposite sides of the shank, and are arranged and adapted to slip loosely into the slots 114 and 115 in the end of the chuck and to bear against the sides of the chuck. The shank of the drill-bit fits loosely in the end of the chuck, and its shank 122 extends through the axial bore 110 of the drill-chuck into the reciprocal path of the piston's hammer-bar, which when the drill-bit is in operative position in the chuck strikes against its end on each and every forward stroke it makes in the cylinder. The drill-bit is thus seated in the chuck in such a manner that it can move axially independent of the chuck, but cannot move rotatively except when it is moved by the chuck which rotates step-by-step with the piston and carries the drill-bit with it, as will be more fully described hereinafter. The projecting lugs on the shank of the drill-bit are made enough shorter than the length of the bifurcation in the end of the chuck to allow the drill-bit a predetermined axial movement of about three-eighths to five-eighths of an inch, and in order to confine the axial movement of the drill-bit under the varying conditions of the forward feed of the drill-cylinder in the shell and the variable forward movement of the drill-bit under the blows of the piston it is necessary to lock it

in the chuck in such a manner that it can move axially about this distance independent of the chuck. For this purpose I employ a chuck-key 127, which is seated in a sleeve-ring 128, 5 that fits loosely in the cap 113. This ring fits between the end of the front cylinder-head and a steel ring 129, and between this steel ring and the bottom of the cap a rubber buffer-ring 130 is placed, which I term the "chuck-buffer." The chuck-key ring comprises a round narrow ring which is provided with an axial bore of two diameters 132 and 133. The bore 132 is intersected by diametrically oppositely-arranged axial slots 134 and 135, which 10 extend in depth to the surface of the largest axial bore, (see Fig. 17, in which a perspective view of the chuck key-ring is shown,) thus dividing the smallest diameter of the bore into two oppositely-arranged semicircular lug portions 136 and 137, the axial center of which is provided with the arcs of an axial bore that is adapted to allow the shank of the drill-bit to extend loosely through the ring-key, while the slots permit the lugs on the 15 drill-bit to pass through the ring-key. The side of the ring that faces the chuck bears loosely against the end of the chuck, and is provided with two projecting lugs 138 and 139, which are arranged diametrically opposite each other, and are adapted and arranged to project loosely over the steps 119 and 120 and to engage the shoulders formed by the junction of these step portions with the larger diameter of the ends of the chuck when the 20 chuck-key ring is turned toward them and to strike against the sides 140 and 141 of the oppositely-arranged ends when turned in the opposite direction. When the chuck-key is turned so that its lugs strike the shoulders formed by the steps 119 and 120, its slots are 25 in line with the slot through the ends of the chuck, and the shank of the drill-bit can be inserted into its operative position with its lugs in the chuck. The key is then turned until its lugs strike the sides 140 and 141, and its slot will then stand at right angles to the slot in the end of the chuck and to the lugs on the drill-bit, and the drill-bit will then be 30 keyed in the chuck against axial displacement, but will still have an axial movement in the chuck sufficient for operative action. The chuck-key can be turned in either direction instantly with the wrench 142, which is provided at one end with oppositely-arranged 35 right-angled fingers 143 and 144, that are adapted to fit in the slots of the chuck-key ring and turn it in either direction. It is not necessary for the operator to look to see if the key-ring is in line with the slot in the chuck when he wishes to insert a drill-bit. He simply inserts by hand the shank of the drill-bit in the key-ring and chuck, passing the projecting lugs on the shank through the radial slots in the key-ring and into the slot in the 40 end of the chuck. After the shank of the

drill-bit has been inserted in the chuck and its projecting lugs have passed through the radial slots in the key-ring should the slot in the end of the chuck not be in alinement with the lugs a slight turn of the drill-bit by the operator's wrist will move the lugs into alinement with the slot, so that they can be inserted. When the slots are in alinement, the side lugs of the key-ring rest close to or substantially against the shoulders of the reduced portion 119 at the end of the chuck, and after the drill-bit's projecting lugs have been inserted into the slot at the end of the chuck the operator gives the drill-bit and the chuck a short quick turn in the direction that will rotate the 45 chuck on its ratchet-teeth far enough to bring the shoulders 140-141 of the chuck against the shoulders of the side lugs of the key-ring, which is prevented from rotating with the chuck by the friction of its surrounding ring 128. The drill-bit is then locked to the chuck, as the slot in the chuck and the projecting lugs on the drill-bit then stand at right angles to the slots in the key-ring. The drill-bit is thus practically instantaneously inserted and 50 locked by the hand of an operator to the drilling-engine. To unlock the drill-bit, the right-angled fingers of the wrench are inserted in the radial slots of the key-ring, and it is turned until its side lugs strike the shoulders on the 55 reduced portion of the chuck, which brings the slots of the key-ring in alinement with the slot in the chuck, and consequently with the lugs of the drill-bit.

I employ a hollow rock-cutting drill-bit in 50 my rock-drilling engine. This drill-bit is provided with an axial hole 121^A, extending through it from end to end, as shown in Fig. 3, and when it is secured in its operative position in the drill-chuck it is in the reciprocal path 105 of the piston and the free end of the water-conveying pipe projects into it. The axial hole in the drill-bit being formed enough larger than the diameter of the pipe to permit a supply of compressed air from the cylinder 110 to flow into it and mingle with water discharged from the water-pipe, as sufficient compressed air passes along the hammer-bar by the loosely-fitting buffer-rings and also through the axial hole in the piston, through 115 which the water-pipe projects for this purpose; but in order to have a positively sufficient supply of compressed air from the cylinder flow directly into the end of the drill-bit I provide the hammer extension of the piston with a 120 channel or groove 139^A, which extends from the front end of the piston to the end of the hammer-bar and forms a direct passage from the cylinder to the hole through the drill-bit, where it mingles and mixes with the water discharging 125 from the water-conveying pipe, and together they are discharged by the air-pressure at each reciprocal stroke of the drilling-engine in spray-like puffs from the cutting-point of the drill-bit into the bottoms of holes in rock, as 130

they are being drilled and wash out the rock-cuttings from the holes as fast as they are made, thus keeping the hole clean and at the same time allaying the dust. The piston-hammer strikes directly on the shank end of the drill-bit, and sufficient clearance is formed in the front cylinder-head and its cap between the projecting shoulder-lugs of the drill-bit and the key-ring to permit of a practical independent longitudinal working movement of the drill-bit, and the drilling-engine is fed forward by means of the feed-screw just fast enough to keep the drill-bit in operative striking relation to the rock and to the full blow of the piston-hammer. When, however, the drill-bit is not against rock, its forward impingements are received by the buffer-ring in the cap, while forward strokes of the piston-hammer are received by the buffer-rings at the forward end of the cylinder.

The valve mechanism herein illustrated and its operation, as well as that of the piston-hammer and the drill-bit, are very clearly illustrated and described in my Patent No. 709,022, dated September 16, 1902, and it is only necessary to mention here that in the preferred construction, which is herein illustrated, the actuating fluid, which may be either air or steam, enters the valve-chest through a pipe or hose which is connected to the entrance 11^A and enters the inlet-port 11, while the opposite end of the hose leads to a supply of compressed air. The compressed air automatically reciprocates the valve and admits air to the opposite ends of the cylinder through the ports 5 and 6 in alternate order and reciprocates the piston-hammer therein against the drill-bit and exhausts through the ports 13 and 14 and the circumferential recess 20 in the piston and the ports 20^A, 20^B, 20^C, and 20^D, and through the two exhaust-ports 13 and 14, and the outlets 13^A and 14^A to the atmosphere in a well-known manner and as described in the above-mentioned patent.

The operation of my automatic air and spring controlled water-governing valve is as follows: As the air flows continuously to the valve-chest of the drilling-engine when turned on to start up and operate the drilling-engine, there is always an air-pressure in the port 11, and a portion of this air flows constantly through the port 18 to the water-valve's stem-actuating piston and moves it against the thimble, and this piston by bearing against the collar 65^A of the valve-stem, which is held against it by the spring 69^A, also moves the valve-stem away from its seat against the water-pipe, and as the air-pressure against the valve-actuating piston is continuous the valve is held open as long as the air is turned on the drilling-engine and it is kept running. The water-inlet valve is held open by the air pressure on its piston, and when the air is shut off from the drilling-engine the valve's piston is pushed back against the partition 61 by the

resilient pressure of the spring 69^A, which also moves the valve-stem against its seat in the entrance to the water-pipe and shuts off the flow of water through the drilling-engine to the drill-bit. Consequently by means of this air-controlled water-inlet valve when the drilling-engine is started up the water-inlet valve is opened, and when the drilling-engine is stopped the water-inlet valve is closed. This feature is of essential value, as it economizes in the use of water in extensive underground or quarry or railway work, where good clean water is scarce, and there is also economy in the use of water when shifting the position of the drilling-engine from one hole to another and when changing drill-bits. The screen also protects the valve-seat from any sand or fibrous matter there may be in the water. The handle at the outer end of the valve-stem allows the valve-stem to be pulled back and turned around on its seat should it stick or any substance should get on the seat that would prevent it from closing tight.

My improved rock-drilling engine represents a simple, durable, compact, light-weight, thoroughly practical rock-drilling engine that will drill with the use of but little air-pressure the largest and deepest holes required in blasting rock in mines, quarries, railroads, and other work.

As the air passes through the ports 5 and 6 a portion of it enters the ports 8 and 9 in alternate order and flows to the ends of the pawl's piston-cylinder 86^B and reciprocates the pawl's piston therein, the air exhausting back through the ports 8 and 9 and 5 and 6 to the atmosphere as the piston reciprocates, causing the pawls to engage in alternate order the ratchet-teeth of the drill-chuck. Thus the pawl 104 on its forward stroke pushes against the tooth 108 in the direction of the arrow F and rotates the chuck a distance equal to the stroke of the piston, while at the same time the pawl 105 is moved backward in position to engage a ratchet-tooth at the opposite side of the drill-chuck and moves against it on the opposite stroke of the pawl-piston and again turns the chuck a distance equal to the stroke of the piston and pawl. I preferably make each tooth of the ratchet of the chuck of a little less length than the stroke of the piston, so that the pawls will surely drop off of them at each stroke of the piston and positively turn the chuck. If desired, however, the pitch of the teeth may be made fine enough to permit the pawls to operatively ride over two or more teeth of the drill-chuck's ratchet-tooth portion at each reciprocal stroke of the pawl's piston. The reciprocative movement of the pawl-piston and its pawls thus rotates the drill-holding chuck at each stroke of the hammer-piston, as the top pawl is forced to turn the chuck by its piston's movement caused by the flow of air through the port 8 into its cylinder when the piston-hammer moves back-

ward, and the bottom pawl is forced to turn the chuck by the opposite stroke of its piston when the air flows into the port 9 on the forward stroke of the piston-hammer, thus 5 rotating the drill-bit-holding chuck and the rock-cutting drill-bit which is locked to it step by step at each stroke or blow of the piston-hammer. The drill-holding chuck and the drill-bit which is locked to it are thus 10 rotated step by step at each and every stroke in either direction the hammer-piston makes in its cylinder by a portion of the actuating fluid operatively reciprocating the pawl's piston in unison with it.

15 My invention greatly simplifies the mechanism commonly used on drilling-engines for intermittently rotating rock-cutting drill-bits. It is also strong, durable, and not liable to get out of order.

20 Having described my invention, what I claim as new, and desire to secure by Letters Patent, is—

25 1. A fluid-pressure drill, comprising a cylinder, a piston having a longitudinal bore, a hollow tool, a water-supply pipe extending into the bore of said piston, and means independent of said piston for rotating said tool, as set forth.

30 2. A fluid-pressure drill, comprising a cylinder, a piston having a longitudinal bore, a hollow tool, a water-supply pipe extending into the bore of said piston, a valve for said pipe, and means whereby the pressure fluid opens said valve when the drill is in operation, 35 as set forth.

35 3. A fluid-pressure drill, comprising a cylinder, a piston having a longitudinal bore, a hollow tool, a water-supply pipe extending into the bore of said piston, a valve for said pipe, and a piston whereby the pressure fluid opens said valve when the drill is in operation, 40 as set forth.

45 4. A fluid-pressure drill, comprising a cylinder, a piston having a longitudinal bore, a hollow tool, a water-supply pipe extending into the bore of said piston, a valve for said pipe, an adjustable spring for closing said valve, and a piston whereby the pressure fluid opens said valve when the drill is in operation, 50 as set forth.

55 5. A fluid-pressure drill, comprising a cylinder, a piston having a longitudinal bore, a hollow tool, a water-supply pipe extending into the bore of said piston, a valve for said pipe, a piston whereby the pressure fluid opens said valve when the drill is in operation, and a valve-stem arranged to slide through the valve-piston for manually operating said valve, as set forth.

60 6. In a rock-drilling engine, the combination with the cylinder and the piston, of a rear cylinder-head having an axial bore in the cylinder end of said cylinder-head, an axial bore in its outer end, a partition between said axial bores having an axial aperture registering

with each bore, a water-inlet hub on said cylinder-head arranged to be connected to a pipe or hose leading to a water-supply under pressure and connected to the cylinder-bore of said cylinder-head, and means for securing 70 said cylinder-head to said cylinder, substantially as described.

7. In a rock-drilling engine, the combination with the cylinder, the piston provided with a longitudinal aperture extending through it 75 and a rock-cutting drill-bit operatively supported in said drilling-engine and provided with a passage leading to its cutting-point, of a rear cylinder-head, means for securing said cylinder-head to said cylinder, a water-conveying pipe secured at one end in the rear end portion of said cylinder and having its opposite end extending through the aperture in said piston and arranged to register with a passage leading to the cutting-point of said 80 rock-cutting drill-bit, a suitable valve arranged to control the entrance to said pipe, means for keeping said valve and said entrance to said pipe closed when said drilling-engine is not in operation and means including a port or passage extending from said cylinder to said valve adapted to admit a supply of the drilling-engine's actuating fluid for opening said valve and for holding said valve open when said drilling-engine is in operation, substantially as described.

8. In a rock-drilling engine the combination with the cylinder having a water-conveying pipe extending through its center, of the piston reciprocally mounted in said cylinder 100 and on said pipe, the rock-cutting drill-bit operatively supported by said cylinder and adapted to be struck by said piston and provided with a passage leading to its cutting-point arranged to register with said pipe and the rear cylinder-head removably secured to said cylinder, a water-inlet in said cylinder-head connecting with said pipe, a valve operatively mounted to control said water-inlet and for keeping it closed when said drilling-engine is not in operation, and means including a port or passage arranged in operative relation to said valve, and adapted to admit a supply of said drilling-engine's actuating fluid, for opening said valve when said drilling-engine is started up and for holding said valve open while said drilling-engine is in operation, substantially as described.

9. In a rock-drilling engine, the combination with the cylinder and the piston provided with an axial aperture extending through it and a hollow rock-cutting drill-bit, of a rear cylinder-head, means for securing said cylinder-head to said cylinder, a bore in the opposite ends of said cylinder-head, a portion between said bores having an axial aperture, a thimble-shaped nut threadedly secured in the outer end of said cylinder-head having an axial bore, a valve-stem slidably supported in said nut and partition and extending beyond each, 125

- a handle on the outer end of said valve-stem, a plug-valve at its inner end, a water-supply pipe secured at one end at the rear end of said cylinder, and having its opposite end project loosely through said aperture in said piston and into said rock-cutting drill-bit, a valve-seat arranged to control the entrance to said pipe and adapted to receive and seat said plug-valve on said valve-stem, a water-inlet in said rear cylinder-head connected with the valved entrance to said water-pipe, means for keeping said valved entrance closed when said drilling-engine is not in operation and means including a piston and a port adapted to permit a supply of the drilling-engine's actuating fluid to the piston for holding said valved entrance to said water-supply pipe open when said drilling-engine is in operation, substantially as described.
- 10 10. In a rock-drilling engine, the combination with the cylinder and the piston reciprocally mounted therein and provided with an axial aperture, of a rear cylinder-head detachably secured to said cylinder, a water-conveying tube secured to the rear end of said cylinder at one end and projecting into the axial aperture in said piston, a valve arranged to control the inlet to said water-tube, a water-inlet in said rear cylinder-head registering with the inlet to said water-tube, a spring arranged to normally hold said valve closed and means including a port extending from said valve-chest to said valve for holding said valve open when said drilling-engine is running, substantially as described.
- 15 11. In a rock-drilling engine, the combination with the cylinder and the piston having an axial aperture therein, of a rear cylinder-head detachably secured to said cylinder, a water-conveying tube extending into the axial aperture of said piston, means for releasably securing the rear end of said tube in the rear end portion of said cylinder, a valve-seat controlling the entrance to said tube, a valve-stem provided with a plug-valve at its inner end axially mounted in said rear cylinder-head in operative engagement with said valve-seat, a spring arranged to normally hold said plug-valve and stem normally against said valve-seat, means including a port or passage adapted to convey a portion of the actuating fluid of said engine to said valve-stem and for moving said valve-stem and its plug-valve end away from said seat, and for holding said valve open while said actuating fluid is operating said rock-drilling engine, and a water-inlet in said rear cylinder-head registering with the inlet to said tube, substantially as described.
- 20 12. In a rock-drilling engine, the combination with the cylinder and the piston, provided with an axial aperture in said piston, of a rear cylinder-head removably secured to said cylinder, a bushing in said aperture, a water-conveying tube having one end and a portion of its length projecting slidably through said bushing and into the axial aperture of said piston, means for releasably securing the opposite end of said tube at the rear end of said cylinder, a valve-controlled inlet to said tube, a valve arranged in said rear cylinder-head to control said inlet, means including a spring for holding said valve normally closed, means including a port extending from said cylinder's valve-chest to said valve to admit a supply of the rock-drilling engine's actuating fluid flowing continuously to said valve when said drilling-engine is in operation for holding said valve open when said rock-drilling engine is in operation, and a water-inlet in said cylinder-head registering with said tube-inlet, substantially as described.
- 25 13. In a rock-drilling engine, the combination with the cylinder and the hammer-piston provided with an axial aperture extending through it, of a rear cylinder-head detachably secured to said cylinder, a disk secured between said rear cylinder-head and said cylinder, a water-conveying tube releasably secured at one end to said disk and having its opposite end projecting loosely into the axial aperture in said piston, a valve-seat arranged in said disk to form the entrance to said tube, a plug-valve and stem reciprocally mounted in said rear cylinder-head in operative engagement with said valve-seat and extending through and beyond said cylinder-head, a handle on the outer end of said valve-stem, a collar on said valve-stem, means including a spring arranged to bear against said collar for normally holding said plug-valve and stem against said seat, means for adjusting the tension of said spring, a partition in said rear cylinder-head positioned between said collar and said valve-seat in which one end of said valve-stem is slidably mounted, a piston reciprocally mounted in said rear cylinder-head between said partition and the collar on said valve-stem and a port extending from the valve-chest of said cylinder to between said partition and the adjacent end of said piston, and arranged and adapted to convey a portion of the drilling-engine's actuating fluid to said valve-stem's piston whereby the valve at the inlet to said tube is opened by the engine's actuating fluid when the drilling-engine is started up and is held open while said drilling-engine is in operation and is closed by said spring when said drilling-engine's actuating fluid is shut off and the engine is stopped and a water-inlet in said rear cylinder-head leading to the valve-controlled inlet to said tube, substantially as described.
- 30 14. In a rock-drilling engine, the combination with the cylinder, the piston and the drill-bit, of a rear cylinder-head detachably secured to said cylinder, an aperture in the cylinder end of said cylinder-head, a disk secured between said cylinder and said cylinder-head, a taper aperture in said disk, a taper plug fitting in said aperture provided with an axial

aperture, slots in said plug extending from its aperture through its peripheral surface, a pipe having one end fitting into the aperture in said plug and its opposite end extending loosely through said cylinder into said drill-bit, means for securing the end of said pipe in said plug, a valve-seat entrance to said pipe in the opposite end of said plug, a suitable valve arranged to control the entrance to said pipe, means for closing and for holding said valve closed when said drilling-engine is not in operation, means for opening and for holding said valve open when said drilling-engine is in operation, and a water-inlet in said cylinder-head registering with said valved entrance to said pipe, substantially as described.

15. In a rock-drilling engine the combination with the cylinder, the piston-hammer, the hollow drill-bit operatively secured to said cylinder in striking relation to said piston-hammer and the rear cylinder-head removably attached to said cylinder-head and having an axial bore in its cylinder end of a disk secured between said cylinder-head and said cylinder provided with a hollow hub portion extending into the bore of said cylinder-head, a circumferential recess round said hub, transverse or radial apertures extending through said hub from the bottom of said recess into its hollow interior and a screen secured round said hub over said circumferential recess, and apertures, substantially as described.

16. In a rock-drilling engine, the combination with the cylinder, the piston-hammer, the hollow drill-bit operatively secured to said cylinder in striking relation to said piston-hammer and the rear cylinder-head removably attached to said cylinder-head and having an axial bore in its cylinder end, of a disk secured between said cylinder-head and said cylinder provided with a hollow hub portion extending into the bore of said cylinder-head, a circumferential recess round said hub, transverse or radial apertures extending through said hub from the bottom of said recess into its hollow interior and a screen secured round said hub over said circumferential recess, and apertures, an axial aperture extending from said hollow hub through said disk, a hollow plug in said aperture, a pipe extending loosely through said piston into the end of said drill-bit and having its opposite end projecting into said plug, and means for securing the end of said pipe in said plug, a valve-controlled entrance within said hollow hub in said plug, a water-inlet in said cylinder-head connecting with the bore in said cylinder-head surrounding the hub of said disk and means for closing and holding said valve-controlled entrance to said plug and pipe closed when said drilling-engine is not in operation and for opening said valve-controlled entrance and holding it open when said drilling-engine is in operation, substantially as described.

17. In a rock-drilling engine, the combina-

tion with the cylinder, the piston-hammer, the hollow drill-bit operatively secured to said cylinder in striking relation to said piston-hammer and the rear cylinder-head removably attached to said cylinder and having an axial bore in its cylinder end, of a disk secured between said cylinder-head and said cylinder, provided with a hollow hub portion extending into the bore of said cylinder-head, a circumferential recess round said hub, transverse or radial apertures extending through said hub from the bottom of said recess into its hollow interior and a screen secured round said hub over said circumferential recess, and apertures, an axial aperture extending from said hollow hub through said disk, a hollow plug in said aperture, a pipe extending loosely through said piston into the end of said drill-bit and having its opposite end projecting into said plug, and means for securing the end of said pipe in said plug, a valve-seat in the end of said plug adjacent to said disk's hollow hub, an axial bore in the rear end of said cylinder-head a partition between the rear bore of said cylinder-head and the bore in its cylinder end, an axial aperture in said partition, a nut threaded in the rear bore of said cylinder-head, a valve-stem slidably mounted in the nut and said partition provided with a valve at its end adapted to register against the valve-seat in said plug, a cupped washer surrounding said valve-stem and secured between the hub of said disk and said partition, a water-inlet in said cylinder-head connecting with the bore in said cylinder-head that surrounds the hub of said disk, means including a spring for holding said valve closed when said drilling-engine is not in operation, and means including a port, whereby a supply of the drilling-engine's actuating fluid for opening and holding said valve open when said drilling-engine is in operation, substantially as described.

18. In a rock-drilling engine, the combination with the cylinder, the piston-hammer, the hollow drill-bit operatively secured to said cylinder in striking relation to said piston-hammer and the rear cylinder-head removably attached to said cylinder and having an axial bore in its cylinder end, of a disk secured between said cylinder-head and said cylinder, provided with a hollow hub portion extending into the bore of said cylinder-head, a circumferential recess round said hub, transverse or radial apertures extending through said hub from the bottom of said recess into its hollow interior and a screen secured round said hub over said circumferential recess, and apertures, an axial aperture extending from said hollow hub through said disk, a hollow plug in said aperture, a pipe extending loosely through said piston into the end of said drill-bit and having its opposite end projecting into said plug, and means for securing the end of said pipe in said plug, a valve-seat in the end of

of said plug adjacent to said disk's hollow hub, an axial bore in the rear end of said cylinder-head, a partition between the rear bore of said cylinder-head and the bore in its cylinder

- 5 end, an axial aperture in said partition, a nut threaded in the rear bore of said cylinder-head, a valve-stem slidably mounted in the nut and said partition provided with a valve at its end adapted to register against the valve-seat in said plug, a cupped washer surrounding said valve-stem and secured between the hub of said disk and said partition, a water-inlet in said cylinder-head connecting with the bore in said cylinder-head that surrounds the 15 hub of said disk, a collar on said valve-stem between said partition and said nut, an expansive coiled spring around said stem between said nut and said collar adapted to hold said valve and stem against the entrance-seat 20 in said plug, a piston slidably mounted in the rear end bore in said cylinder-head between said partition and said collar and a port or passage extending from the rear end bore of said cylinder-head adjacent to said partition 25 and the adjacent end of said piston to said cylinder's valve-chest's air-inlet port whereby when the drilling-engine is not in operation said spring holds said valve closed, and when said drilling-engine is started up, the air flowing to the said piston opens and holds said valve open while said drilling-engine is running, substantially as described.

19. In a rock-drilling engine, the combination with the cylinder, the piston and the drill-bit, of the rear cylinder-head and the ring threaded to the end of said cylinder and arranged to clamp said cylinder-head to said cylinder, a water-inlet in said cylinder-head, a pipe supported at one end between said cylinder-head and said cylinder and projecting loosely through said piston into said drill-bit, a valve operatively mounted in said rear cylinder-head and arranged to control the entrance to said pipe and projecting through 45 and beyond said cylinder-head, a spring arranged to normally hold said valve closed, means including an air-port extending from said valve to said cylinder's valve-chest for opening and holding said valve open when 50 said drilling-engine is in operation and a handle secured to the outer end of said valve-stem adapted to permit said valve to be manually opened and rotated on its seat, and a water-inlet in said cylinder-head connecting with 55 said valve-controlled entrance to said pipe, substantially as described.

20. In a rock-drilling engine, the combination with the cylinder, the piston, the rear cylinder-head and the clamping-ring, of the valve-stem, the thimble-nut and the spring, substantially as described.

21. In a rock-drilling engine, the combination with the cylinder, the piston, the rear cylinder-head provided with a water-inlet and the clamping-ring, of the valve-stem, the thim-

ble-nut threaded into the end of said cylinder-head and provided with a check-nut adapted to secure said thimble-nut in adjusted positions, the valve-stem's piston, the cupped washer on said valve-stem, the disk secured 70 between said cylinder and said rear cylinder-head, the pipe-holding plug secured in said disk and provided with a valve-seat arranged in operative relation to said valve-stem, substantially as described.

22. In a rock-drilling engine, the combination with the cylinder, the piston and the hollow drill-bit, of the rear cylinder-head provided with a water-inlet, the ring for securing said cylinder-head to said cylinder, the 80 disk secured between said cylinder-head and said cylinder, an aperture in said disk, a taper plug extending through said disk, a thread and nut on the cylinder end of said plug, an aperture through said plug, slots through the 85 periphery of said plug, a valve-seat in the end of said plug, the valve seated in said cylinder-head and in said plug, the water-passage from said valved entrance to said plug to said water-inlet of said cylinder-head and 90 the water-pipe clamped to said split plug by said nut at one end, extending loosely through said piston into said hollow drill-bit, substantially as described.

23. In a rock-drilling engine, the combination with the cylinder, the piston, the drill-bit, the rear cylinder-head and the ring arranged to removably secure said cylinder-head to said cylinder, of a disk clamped between said cylinder and said cylinder-head, a hub on said 100 disk projecting into said head, a water-chamber in said cylinder-head surrounding said hub, a water-inlet in said cylinder-head connecting with the water-chamber surrounding said hub, water-passages extending through 105 the shell of said hub into its interior, a screen over said water-passages, a removable valve-seat plug in the axial center of said disk provided with an axial bore, a water-conveying pipe extending at one end into said valve-seat 110 plug, means for removably securing said pipe to said valve-seat plug and having its opposite end projecting loosely through said piston into said drill-bit, a plug-valve and stem arranged in said cylinder to operatively engage 115 the valve-seat in said plug, and control the water-inlet to said water-pipe, means for packing said valve-stem, a spring arranged to normally hold said plug-valve closed, and means including an air-port extending from said 120 valve through said rear cylinder-head to the air-supply port of said drilling-engine, whereby a supply of the drilling-engine's actuating compressed air is admitted to open and to continuously hold open said water-inlet valve 125 when air is turned on to start said rock-drilling engine and while the same is in operation, substantially as described.

24. In a rock-drilling engine, the combination with a cylinder, an operative piston re- 130

ciprocally mounted in said cylinder, a rock-cutting drill-bit operatively supported by said cylinder in the reciprocal striking path of said piston and provided with a fluid-passage extending to its cutting-point, of a water-inlet at the rear end of said cylinder, a water-conveying pipe or passage in said cylinder arranged and adapted to operatively convey water to the fluid-passage in said drill-bit, and a valve arranged in the rear end of said cylinder

der and arranged and adapted to control the water entrance to said pipe or passage, substantially as described.

In testimony whereof I affix my signature in presence of two witnesses.

JOHN GEORGE LEYNER.
